CLAIM

The ornamental design for a synthetic resin sheet material, as shown and described.

DESCRIPTION

FIG. 1 is a front view of a synthetic resin sheet material of the present invention.

FIG. 2 is a front reference view of the synthetic resin sheet material of FIG. 1.

FIG. 3 is a rear view of the synthetic resin sheet material of FIG. 1.

FIG. 4 is a front perspective view of the synthetic resin sheet material of FIG. 1.

FIG. 5 is a rear perspective view of the synthetic resin sheet material of FIG. 1.

FIG. 6 is an enlarged detail view of the area designated by line 6-6 within FIG. 2 of the synthetic resin sheet material of FIG. 1.

FIG. 7 is an enlarged detail view of area 7 circumscribed within FIG. 2 of the synthetic resin sheet material of FIG. 1; and,

FIG. 8 is an enlarged detailed view of the area designated by line 8-8 within FIG. 2 of the synthetic resin sheet material of FIG. 1.

For clarity, the synthetic resin sheet material is shown within a dark background environment that forms no part of the claimed design.
